(57) **CLAIM**

The ornamental design for a display of a vehicle steering wheel with icon, as shown and described.

DESCRIPTION

FIG. 1 is a front view of a display of a vehicle steering wheel with icon in accordance with my new design;

FIG. 2 is a perspective view of the display of the vehicle steering wheel with icon in accordance with my new design; and,

FIG. 3 is an enlarged view of the icon in accordance with my new design, which is displayed in the display of a vehicle steering wheel along the lines 3-3 of FIG. 1.

The dash-dash broken lines in FIGS. 1 and 2 represent the vehicle steering wheel and form no part of the claimed design.

1 Claim, 3 Drawing Sheets**FIG. 1**

FIG. 2

FIG. 3
